US0D1059034S

(12) **United States Design Patent** (10) **Patent No.:** **US D1,059,034 S**
(45) **Date of Patent:** **** Jan. 28, 2025**

(54) **DUFFEL BAG**

(71) Applicant: **YETI Coolers, LLC**, Austin, TX (US)

(72) Inventors: **Donald Edward Desroches**, Austin, TX (US); **John Warren Dow**, Austin, TX (US); **Calvin Tabor**, Austin, TX (US)

(73) Assignee: **YETI Coolers, LLC**, Austin, TX (US)

(**) Term: **15 Years**

(21) Appl. No.: **29/900,205**

(22) Filed: **Aug. 17, 2023**

Related U.S. Application Data

(63) Continuation of application No. 29/838,968, filed on May 17, 2022, now Pat. No. Des. 1,000,834, which is a continuation of application No. 29/762,930, filed on Dec. 18, 2020, now Pat. No. Des. 955,746.

(57) **CLAIM**

The ornamental design for a duffel bag as shown and described.

DESCRIPTION

FIG. 1 is a front perspective view of a duffel bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines show portions of the duffel bag, including stitching, that form no part of the claimed design. The uneven-length broken lines show the boundaries of the claimed design and form no part thereof.

1 Claim, 6 Drawing Sheets
